(57) **CLAIM**

The ornamental design for a 5 head halo projector floor lamp, as shown and described.

DESCRIPTION

FIG. 1 is a perspective view of a 5 head halo projector floor lamp showing my new design;

FIG. 2 is a front elevational view thereof;

FIG. 3 is a rear elevational view thereof;

FIG. 4 is a left view thereof;

FIG. 5 is a right view thereof;

FIG. 6 is a top plan view thereof;

FIG. 7 is a bottom plan view thereof;

FIG. 8 is an enlarged view of portion 8 of FIG. 4 thereof; and,

FIG. 9 is an enlarged view of portion 9 of FIG. 6 thereof. The broken lines illustrate portions of the 5 head halo projector floor lamp that form no part of the claimed design.
